UNITED STATES PATENT OFFICE.

ROBERT R. RUST, OF NEW YORK, N. Y.

PLUMBING SYSTEM.

Application filed April 27, 1923. Serial No. 634,941.

Fig. 1 is an elevation showing a plumbing system embodying my invention; Fig. 2 is an elevation of a modification thereof; Fig. 3 is an elevation of a further modification; Fig. 4 is an elevation of a still further modification; and Fig. 5 is a section on line 5—5 of Fig. 4.

My invention relates to a plumbing system for buildings and comprises two stacks 10 so arranged and connected that one stack when used for waste will be vented by the other stack and will thereby prevent back pressures and siphoning of the various fixtures connected with such stacks. My invention in effect may utilize the vent stack as a waste stack and it may provide such connections between waste and vent stack as to eliminate the occurrence of excessive pressures or vacuums; in any event, provision is 20 made for adequate venting so that in such a system I am enabled to connect a much greater number of fixtures than can be employed in the usual vented system. My invention also comprises the various features 25 which I shall hereinafter describe and claim.

Referring to the drawings, 2 indicates a stack having waste, soil pipe and vent connections 4, 5 and 6, respectively, with the fixtures on alternate floors, and 3 indicates a 30 similar stack having waste connections with the fixtures on the intermediate floors. The floors are indicated by dotted lines. The stacks 2 and 3 are connected by the crossovers 7, so that when the waste descends 35 through the stack 3 the stack 2 will be vented through the crossovers 7 by the stack 3, and vice versa. The crossovers 7 are of inverted V-shape to prevent stoppage from the waste or flowing from one stack into another. The arrangement of having main fixture connections with one stack on alternate floors tends to eliminate the possibility of 40 back pressures or siphoning. I have indicated a connection 8 with a basin fixture leading into the stack 3, as a matter of convenience. The sections 9 of the stacks 2 and 45 3 are preferably connected by the webs 10, so that in erecting the stacks 2 and 3 there will be no difficulty in aligning the various sections. The crossovers 7 perform a like office 50 for the intermediate stack sections.

In Fig. 2 I have shown an arrangement similar to Fig. 1 with the soil pipe connections 5' all arranged in the stack 3' and the 55 basin and bath-tub connections leading into the stack 2'. The crossovers 7', as in Fig. 1,

are of inverted V-shape so as to prevent the waste from the stack 2' clogging the crossovers 7' or flowing into the stack 3'. As in Fig. 1, the stack 3' will vent the stack 2', and vice versa.

In Fig. 3 I have shown the stack 2'' as being used exclusively for a waste line and the stack 3'' as a vent line. In this arrangement the crossovers 7'' are arranged at an angle so as to prevent the waste from flowing 65 into the vent line.

In Figs. 4 and 5 I have shown the two stacks cast in a single pipe, which in cross-section is in form like the numeral 8''. In 70 this modification the waste and soil pipe branches 4'' and 5'' open into the stack 2''. Connecting openings or crossovers 7'' are provided through the intervening web 11 so as to permit proper venting. This form of 75 my invention provides a very compact system which occupies a minimum of space within the walls of the building. It may also be cast readily.

My invention provides a plumbing system 80 which is very simple in design, is readily installed, provides ample venting, and at the same time utilizes the stacks to their full capacity. A further advantage in my improved system lies in the fact that it is never 85 necessary to carry a vent line around the waste stack to reach the vent stack. Instead of having to use a jump-over I connect directly with a vent branch 6, 6', 6'' or 6''' in 90 the side of the nearest stack, as is shown in Figs. 1, 2, 3 and 4 respectively.

As exemplified in the various forms here shown my invention is particularly adapted to provide effective venting by reason of its arrangement of crossovers, which are located 95 at short distances above and below the waste branch openings into the stacks. If the waste running from any fixture creates a plus pressure by forcing air in front of or below it as it runs down a stack, such air 100 under pressure will pass through the crossover lying immediately below it, and then as the rush of the waste down the stack has caused a minus pressure or a partial vacuum above or behind it in the stack, the air will 105 rush back into the stack from which it has been expelled through the crossover next above, thus almost instantaneously equalizing pressures and preventing the consequent back pressure or siphonage in the fixtures. 110

With systems constructed in accordance with my invention the vent branches 6 con-

necting with the fixtures may, if desired, be omitted, as the crossover connections are arranged above and below each waste branch in such manner as to provide, with the section of stack arranged parallel to the stack containing such branch a complete loop, which gives such effective venting as to eliminate substantially back pressures and siphonage.

10 The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

- 20 1. In a plumbing system, a pair of stacks extending from floor to floor and having a multiple number of crossover connections between adjacent floors, whereby the pressures in the two stacks are equalized, at least one of the stacks having lateral branches for connection with fixtures.
- 25 2. In a plumbing system, a pair of waste stacks, each stack having lateral waste branches for connection with fixtures, and connections between stacks comprising means whereby one stack will act as a pressure equalizer for the other stack.
- 30 3. In a plumbing system, a pair of stacks extending from floor to floor, comprising sections; one of the sections forming portions of both stacks and containing a waste branch intended for connection with a fixture; other sections above and below the waste branch section directly connected therewith, each forming a portion of both of said stacks, and having a crossover connection between said stacks adjacent the waste branch section, the two crossover connections and the stacks with which they are connected forming a loop to equalize pressures in the said stacks in the region of the waste branch section.
- 35 4. In plumbing systems, a pair of vertically extending stacks arranged in parallel, each stack having waste and vent connections

arranged on alternate floors, and crossovers between stacks to permit pressure in one stack to be equalized with pressures in the other.

5. In plumbing systems, a plurality of ⁵⁵ fittings, each comprising sections of a pair of stacks, one of the fittings containing two crossovers and another of said fittings having waste branches, said fittings when assembled comprising a pair of continuous ⁶⁰ stacks having waste branches at each floor and crossover connections from one stack to the other between said floors.

6. In plumbing systems, a plurality of ⁶⁵ fittings, each comprising integral sections containing a pair of stacks, one of the fittings containing crossover pressure equalizing connections between stacks, and another of said fittings having waste branches for connection with fixtures.

7. In plumbing systems, a plurality of ⁷⁰ fittings, each comprising sections of a pair of stacks, spacing connectors between the stacks, the spacing connectors in one of the sections comprising pressure equalizing connections leading from one stack into the other, branches for waste or vent connections being also provided in one of the sections.

8. In a plumbing system, a pair of stacks ⁸⁰ arranged substantially in parallel extending from floor to floor, a waste branch from one of the stacks for connection with a fixture, a crossover connection between the stacks arranged immediately above said branch, and another cross connection immediately below said branch, the said crossovers acting to equalize pressures between the stacks in the region of the waste branch portion.

9. In a plumbing system, a pair of stacks ⁹⁰ extending from floor to floor comprising sections, one of the sections forming portions of both stacks and containing two crossover connections between said stacks to permit equalization of pressures therebetween, said section having also a vent connection with a fixture, and another of said sections also forming portions of both stacks having a waste branch.

ROBERT R. RUST.
